UNITED STATES PATENT OFFICE

1,931,205

CALENDAR STAND

Carlyle N. Montanye, Baltimore, Md.

Application April 18, 1933. Serial No. 666,729

2 Claims. (Cl. 40—121)

The invention relates to improvements in desk stands and the like used for holding calendar pads, and it is the object of said invention to provide a new and improved stand in which the pad does not project appreciably beyond the face of the pad-carrying plate, and in which the leaves of the pad are effectively held at their lower edges so that they will not upwardly curl.

With the foregoing in view, the invention resides in the novel subject matter hereinafter described and claimed, description being accomplished by reference to the accompanying drawing.

Fig. 1 is a front elevation of a calendar pad stand constructed in accordance with the invention.

Fig. 2 is a vertical sectional view on line 2—2 of Fig. 1.

Fig. 3 is a view similar to Fig. 1 but showing a slightly different construction.

In the preferred manner of constructing the article, it is stamped from a single plate of sheet metal or any other appropriate material. The plate is denoted at 5 and it may be shaped and ornamented in any desired way. It is preferably provided with a stamped out leg 6 for holding it in a substantially upright position, and with an opening 7 so that it may be hung if desired.

Plate 5 is provided with a rectangular countersunk portion 8 to receive a calendar pad 9, and appropriate fasteners 10 are employed for securing the upper edge of said pad to said plate. The portion of the plate at the lower edge of the countersunk portion 8 carries two tongues 11 (in a

relatively long article such as shown in Fig. 1) or a single tongue 12 (in a shorter article such as seen in Fig. 3). The tongues 11 or 12 project upwardly in forwardly spaced relation with the countersunk portion 8 to lie against the front side 60 of the pad 9, at the lower edge of the latter. These tongues therefore effectively hold the pad leaves from upwardly curling.

In Figs. 1 and 2, the tongues 11 are stamped from the countersunk portion 8 and the front 65 sides of said tongues are convex. In Fig. 3, the tongue 12 is also stamped from the countersunk plate portion 8, but said tongue is provided with a flat front side. Obviously, however, the tongues could be of shapes other than shown.

The invention provides an exceptionally simple and inexpensive calendar pad support embodying a novel anti-curl feature which is greatly advantageous over similar holders having no provision to prevent curling of the leaves.

I claim:—

1. A calendar holder comprising a plate having a countersunk portion to receive a calendar pad, means for fastening the upper edge of the pad to said plate, and at least one tongue carried by 80 the portion of the plate at the lower edge of said countersunk portion, said tongue projecting upwardly in forwardly spaced relation with said countersunk portion to lie against the front side of the pad at the lower edge of the latter, preventing the pad leaves from curling upwardly.

2. A structure as specified in claim 1; said tongue being stamped from said countersunk portion of said plate.
